CLAIM

The ornamental design for a pet toy and dental hygiene device, as shown and described.

DESCRIPTION

FIG. 1 is a perspective view of a pet toy and dental hygiene device, showing my new design.

FIG. 2 is another perspective thereof;

FIG. 3 is a bottom perspective view thereof;

FIG. 4 is a top perspective view thereof;

FIG. 5 is an enlarged top perspective view thereof;

FIG. 6 is a front elevation view thereof;

FIG. 7 is a side elevation view thereof;

FIG. 8 is a bottom plan view thereof;

FIG. 9 is a top plan view thereof

FIG. 10 is a cross-sectional top perspective view taken along and in the direction of line 10-10 in FIG. 4.

FIG. 11 is another perspective view of FIG. 10 thereof, shown rotated for completeness of illustration.

FIG. 12 is another perspective view of FIG. 10 thereof, shown rotated for completeness of illustration.

FIG. 13 is a front elevation view of FIG. 10 thereof, shown rotated for completeness of illustration.

FIG. 14 is a side elevation view of FIG. 10 thereof, shown rotated for completeness of illustration.

FIG. 15 is a bottom plan view of FIG. 10 thereof, shown rotated for completeness of illustration; and,

FIG. 16 is a top plan view of FIG. 10 thereof, shown rotated for completeness of illustration.
